UNITED STATES PATENT OFFICE.

COLEMAN W. SUMNER, OF TEXOLA, OKLAHOMA.

PETCOCK.

1,283,957.

Specification of Letters Patent.

Patented Nov. 5, 1918.

Application filed March 12, 1918. Serial No. 221,977.

To all whom it may concern:

Be it known that I, COLEMAN W. SUMNER, a citizen of the United States, residing at Texola, in the county of Beckham and State 5 of Oklahoma, have invented a new and useful Petcock, of which the following is a specification.

This invention relates to an improved petcock particularly designed for use on the 10 transmission casing of the well known Ford automobile. Two oil petcocks are used in the machine mentioned, one being located above the other. The lower one, however, often is rubbed open accidentally, thereby releasing 15 the lubricating oil and resulting in injury to the bearings of the machine. It is an object of the present invention to provide a petcock which can be substituted readily for the upper petcock already in use, and which 20 has means for engaging the lower drain cock, thus to lock both valves against accidental opening.

With the foregoing and other objects in view which will appear as the description 25 proceeds, the invention consists of certain novel details of construction and combinations of parts which will be hereinafter more fully described and pointed out in the claim, it being understood that various 30 changes may be made within the scope of the appended claim without departing from the spirit of the invention.

In the accompanying drawing the preferred form of the invention has been shown.

35 In said drawings—

Figure 1 is a face view of a portion of the transmission casing of a Ford automobile and showing the present improvements applied thereto.

40 Fig. 2 is a side elevation of the improved structure, the adjacent portion of the casing being shown in section.

Referring to the figures by characters of reference, 1 designates a portion of a trans-

mission casing and 2 designates the usual 45 lower drain cock used in connection therewith. The ordinary upper drain cock is removed and the device constituting the present invention is substituted therefor. The improved cock 3 has a channeled strip 50 4 pivotally connected to the flattened head thereof as shown at 5 and this strip is of sufficient length to engage and straddle the head of the cock 2 when the two cocks are in closed position. A coiled spring 5 is secured 55 at one end to the strip 4 and at its other end of the stem 6 of the cock 3 at that end thereof remote from the head.

When it is desired to apply the present improvements to a Ford automobile, the upper 60 drain cock is removed from the transmission casing and the improved cock 3 is substituted therefor. By turning the two cocks so that the channeled strip 4 will straddle the head of the lower cock 2, where it will be 65 held by the spring 5, both cocks will be held in closed positions and to open either of them it is first necessary to swing the strip 4 out of engagement with the head of the cock 2. 70

What is claimed is:—

The combination with spaced petcocks each having a stem and a flattened head, of a channeled strip pivotally connected to the head of one of the petcocks and adapted 75 to straddle the head of the other petcock, and a spring connection between said strip and the stem of the head to which it is pivoted for holding the strip yieldingly in engagement with the other head. 80

In testimony that I claim the foregoing as my own, I have hereto affixed my signature in the presence of two witnesses.

COLEMAN W. SUMNER.
